UNITED STATES PATENT OFFICE.

EDWARD L. BOWES, OF ST. LOUIS, MISSOURI.

DOOR-LATCH.

936,214.

Specification of Letters Patent.

Patented Oct. 5, 1908.

Application filed December 11, 1908. Serial No. 467,111.

To all whom it may concern:

Be it known that I, EDWARD L. BOWES, a citizen of the United States, and resident of St. Louis, Missouri, have invented certain new and useful Improvements in Door-Latches, of which the following is a specification containing a full, clear, and exact description, reference being had to the accompanying drawings, forming a part hereof.

My invention relates to a door latch particularly invented for use in connection with doors which are hinged to swing open in both directions, and which doors are in use on the present type of pay-as-you-enter cars.

In certain types of pay-as-you-enter cars it is essential that an entrance door be provided which can be readily swung inward to allow the entrance of passengers, and which door is normally held against swinging outward until considerable pressure is applied to the inside of the door, and it is the object of my invention to provide a simple, inexpensive latch which is seated in the door post against which the free edge of the door swings, and which latch normally holds the door in a closed position and permits said door to be opened inward with a slight pressure and to open outward with comparatively greater pressure from the inside.

To the above purposes, my invention consists in certain novel features of construction and arrangement of parts which will be hereinafter more fully set forth, pointed out in the claims, and illustrated in the accompanying drawings, in which:

Figure 1 is a horizontal section taken through a portion of a street car of the pay-as-you-enter type, and showing the entrance door held in a closed position by my improved latch; Fig. 2 is an enlarged vertical section taken on the line 2—2 of Fig. 1; and Fig. 3 is a horizontal section taken on the line 3—3 of Fig. 2.

Referring by numerals to the accompanying drawings: 1 designates the corner post of the car body, and hinged thereto so as to swing open in both directions in the entrance door 2, the free edge of which closes against a post 3 located at the end of the car body, and seated in the free edge of the door 2 is a metal block 4, provided with an integral tongue 5. Formed in the post 3 in horizontal alinement with this block 4 is a pocket 6, in which is positioned a latch housing 7, approximately rectangular in form, and ar-

ranged to swing in a horizontal plane on a vertically disposed pivot pin 8 seated in the forward end of the housing 7, is a latch plate 9, the forward portion of which projects beyond the face of the housing 7, and said projecting forward portion being provided with the curved bearing faces 10 between which is formed a notch 11, of such size as to readily receive the tongue 5.

The rear side 12 of the latch plate 9 is perfectly straight, and bearing thereagainst are the forward ends of a pair of horizontally disposed pins 13 and 13^a, which are arranged to slide freely through the block 14 arranged within the housing 7, and the rear portions of these pins are reduced in diameter relative to the forward portions thereof, and said reduced rear portions are arranged to slide through sleeves 15, which are adjustably arranged in the rear end wall of the housing 7. Located on the reduced portions of these pins 13 and 13^a and bearing against the forward ends of the sleeves 15 are washers 16, and positioned on the pin 13 and interposed between the washer thereon and the shoulder between the large and small portions of said pin is a light expansive coil spring 17, and positioned on the corresponding portion of the opposite pin 13^a is a heavy expansive coil spring 18.

When a door latch of my improved construction is applied for use, the parts occupy the positions as seen in Figs. 2 and 3, and the latch plate 9 is held with the notch 11 occupying a central position, said notch being occupied by the tongue 5. Passengers entering the car press against the outside face of the door 2, and as a result the tongue 5 bears against the side of the notch 11 in such a manner as to swing the latch plate 9 on its pivot pin 8 into the position shown by dotted lines in Fig. 3, which action forces the pin 13 rearward, this compressing the coil spring 17, and as said spring is comparatively light, but little resistance is offered to the pressure applied to the door to release the free edge thereof from the latch and to swing said door inward to an open position. When the door 2 automatically returns to a closed position, the tongue 5 will bear against the corresponding portion of the curved face 10 on the projecting portion of the latch plate 9, and this end of the latch plate will be forced inward to permit the tongue 5 to pass the shoulder between the curved face and the notch 11, and as soon as

the tongue occupies said notch the latch plate will return to its normal position by reason of the pressure exerted by the spring 17. The heavy spring 18 normally holds the latch plate 9 against swinging into such position as to permit the tongue 5 to disengage from the notch 11 to permit the door to swing outward into an open position, but should it be found necessary to swing said door outward into an open position, a heavy pressure applied to the inside of the door will cause the latch plate 9 to swing horizontally upon its pivot pin in such a manner as to force the pin 13^a rearward against the pressure exerted by the heavy coil spring 18, and thus the door can be swung outward to permit the exit of passengers.

A door latch of my improved construction is very simple, is automatic in its action and 20 is particularly adapted for the entrance doors of pay-as-you-enter cars, which entrance doors are designed to open inward with slight pressure, and to open outward when subjected to comparatively great 25 pressure.

I claim:

1. The herein described door latch, comprising a housing, a latch plate pivotally arranged in the housing and adapted to engage the door, and a pair of spring pressed members bearing against the rear side of the latch plate.

2. The herein described door latch, comprising a housing, a latch plate pivotally arranged in the housing and adapted to engage the door, a pair of spring pressed members bearing against the rear side of the latch

plate, and the springs on said spring pressed members being of different tension.

3. The herein described door latch, comprising a housing, a latch plate pivotally mounted therein, and adapted to engage the edge of a door, a pair of pins bearing against the rear side of the latch, springs arranged on said pins, which springs are of different tension, and adjustable means whereby the tension of the springs is regulated.

4. The combination with a door post and door, of a housing positioned in the door post, a latch plate pivotally mounted in the 50 housing, in which latch plate is formed a notch, spring pressed members engaging against the latch plate, a block carried by the door, and a tongue integral with said block, which tongue engages in the notch in 55 the latch plate.

5. A door latch of the class described, comprising a housing, a latch plate pivotally mounted therein, in which latch plate is formed a notch, a pair of pins arranged 60 to slide in the housing and bearing against the rear side of the latch plate, springs arranged on said pins, which springs are of different tension, means whereby the tension of said springs is adjusted, and a tongue 65 carried by the door and adapted to normally engage in the notch of the latch plate.

In testimony whereof, I have signed my name to this specification, in presence of two subscribing witnesses.

EDWARD L. BOWES.
